DESIGN FOR A SIGNAL LAMP FOR AUTOMOTIVE VEHICLES

Bornett L. Bobroff, Racine, Wis.

Application March 6, 1936, Serial No. 61,504

Term of patent 14 years

To all whom it may concern:

Be it known that I, Bornett L. Bobroff, a citizen of the United States, residing at Racine, in the county of Racine and State of Wisconsin, have invented a new, original, and ornamental Design for a Signal Lamp for Automotive Vehicles, of which the following is a specification, reference being had to the accompanying drawing, forming part thereof:

In the accompanying drawing, Figure 1 is a side elevation of a signal lamp for automotive vehicles showing my new design.

Figure 2 is a plan view thereof.

The design on the front and rear face of the directional signal lamp is the same as shown in Figure 1. The arrow shown in the design is a dominant feature of the design.

I claim:

The ornamental design for a signal lamp for automotive vehicles as shown and described.
